PROCESS AND APPARATUS FOR CRACKING OIL

Original Filed Dec. 6, 1920

UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR CRACKING OIL

Application filed December 6, 1920, Serial No. 428,787. Renewed May 25, 1929.

This invention relates to improvements in a process and apparatus for cracking oil, and refers more particularly to the conversion of such petroleum constituents as fuel oil and heavy asphaltic crudes into lighter hydrocarbons, such as gasoline, kerosene, gas oil and the like, although in its broadest aspects the invention relates to the conversion of heavy to lighter hydrocarbons. In the cracking of petroleum oil, certain of the generated vapors are insufficiently converted, and it is desirable to return them to the system for further treatment. The heavier vapors so returned are known as reflux condensate for the reason that they are the result of reflux condensation in one form or another. This reflux condensate is of a different character than the raw oil from which it originally came, and in many types of oils, should be, if possible, subjected to different conditions of cracking, particularly as to temperature and pressure, than should the raw oil itself. At the same time, it is desirable to treat the oil in an economical and simple apparatus, as the cost of construction and maintenance of apparatus for cracking oil is an item of such moment as to frequently make the process, however desirable in itself, commercially not feasible. The present invention overcomes this objection, and at the same time treats the reflux condensate under independently regulated conditions as to temperature and pressure.

In the drawings, the single figure is a view partly in side elevation and partly in vertical section of my improved apparatus.

Referring to the drawings, 1 designates the furnace, provided with a pair of combustion chambers 2 and 3, preferably separated by means of a foraminated bridge wall 4. The combustion chambers are respectively provided with the oil or gas burners 5 and 6, and the furnace is provided with a stack 7. In the lower chamber is mounted the raw oil heating coil 8, which may take the form of several hundred feet of four-inch pipe, the inlet side of which is connected by feed line 9 to raw oil pump 10, provided with throttle valve 11. This raw oil pump is connected to any suitable source of raw oil supply. The upper end of the coil 8 is provided

with a discharge line 12, in turn connected to the main transfer line 13, leading to the expansion chamber 14 located outside of the fire zone. A throttle valve 15 is interposed in the line 13. In the transfer line 12 is interposed a pump 16, provided on either side with valves 17 and 18. The pump may be bypassed through bypass line 19, having throttle valve 20. The arrangement is such that the oil may be delivered from the coil 8 to the expansion chamber either at the same pressure as in the coil or at a reduced pressure or at an increased pressure relative to the coil.

The lower end of the expansion chamber is provided with a residue draw off line 21, having throttle valve 22. It is also provided with a vapor outlet pipe 23, having throttle valve 24, and leading to the lower end of dephlegmator 25, which dephlegmator is provided with the alternately disposed baffles 26. The upper end of the dephlegmator is provided with vapor outlet pipe 27, having throttle valve 28, and leading to the condenser coil 29, seated in condenser box 30.

The lower end of the coil 29 is connected by pipe 31, having throttle valve 32, to the upper end of the receiver 33. This receiver 33 has a liquid draw off pipe 34, controlled by throttle valve 35, gas outlet pipe 36, controlled by throttle valve 37. It is also provided with liquid level gauge 38.

The reflux condensate is drawn off from the bottom of the dephlegmator through reflux line 39, having throttle valve 40, and leading to the inlet side of feed pump 41. The discharge side of the pump 40 is connected by means of feed line 42, having throttle valve 43, to the lower end of a heating coil 44, seated in the combustion chamber 3. This coil 44 may be of the same length and size as the coil 8, or it may be of increased diameter or increased length of pipe, particularly if there is more reflux condensate to be treated than raw material. In the cracking of certain petroleums this will be the case, the amount of reflux, of course, depending also upon the temperature and size of the dephlegmator, the desired end point product to be obtained, as well as upon the temperature and pressure to which the raw

oil is subjected. In other words, all factors must be taken into consideration in regulating the size of the coils relative to each other. From extended practical experience in the cracking of petroleum oil, it is impossible to definitely give figures for all oils, but anyone skilled in the art will have no difficulty in regulating these features.

The other end of the coil 44 is connected 10 by pipe 45 to the main transfer line 13. A pump 46, having at either side valves 47 and 48, is interposed in the line 45. The pump may be bypassed by means of the bypass pipe 49, in which is interposed throttle valve 50. The arrangement is such that the re-heated reflux condensate may be delivered 15 from the coil 44 to the expansion chamber under the same, increased or decreased pressure relative to the pressure in the heating 20 coil.

Suitable pressure gauges 51 are provided in various parts of the system as shown.

In carrying out the process, raw oil, as for example Kansas or Oklahoma gas oil of 25 degrees Baumé gravity, may be continuously fed through the first heating coil, and there subjected to a temperature of say 750 degrees F., care being taken to deliver it in substantially liquid condition to the expansion 30 chamber. The reflux condensate may be heated to a temperature varying between 600 and 800 degrees F. A uniform pressure, if desired, may be maintained on the entire system clear through to the receiver, as for 35 example, 130 pounds. A process may be carried out with this apparatus in which the pressure on the raw oil coil may be say 150 pounds, 200 pounds on the reflux condensate coil, and 100 pounds on the expansion chamber, dephlegmator and condenser. One pronounced advantage of the present invention 40 is the ability to subject the reflux condensate in the same apparatus and in the same furnace to independently regulated conditions 45 of temperature and pressure relative to that to which the raw oil is first subjected.

I claim as my invention:

1. A process for converting oil, comprising 50 passing a stream of charging oil through a heating zone to be subjected to a temperature sufficient to vaporize a substantial part thereof, in introducing the heated hydrocarbons under a pressure, in excess of that maintained on the charging oil during passage through the heating zone, to an enlarged expansion chamber where vaporization occurs, in subjecting the vapors to dephlegmation, in heating the reflux condensate in a separate stream to a cracking temperature, in 55 passing the heated reflux condensate under pressure to said expansion chamber, and in withdrawing the unvaporized residual oil from the expansion chamber.

2. A process for converting oil, comprising 60 passing a stream of charging oil through

a heating zone to be subjected to a temperature sufficient to vaporize a substantial part thereof, in introducing the heated hydrocarbons under a pressure, in excess of that maintained on the charging oil during passage through the heating zone, to an enlarged expansion chamber where vaporization occurs, in subjecting the vapors to dephlegmation, in heating the reflux condensate in a separate stream to a cracking temperature while maintained under a pressure in excess of the pressure on the charging oil passing through the heating zone, in passing the heated reflux condensate to said expansion chamber, in withdrawing the unvaporized residual oil from the expansion chamber, and in maintaining a superatmospheric pressure on the oil undergoing conversion.

3. A process for cracking hydrocarbon oil, comprising the simultaneous and independent subjection of a relatively low boiling point hydrocarbon oil and a relatively high boiling point hydrocarbon oil to higher and lower cracking conditions of temperature and pressure respectively, thereafter commingling the heated oils in a common zone maintained under a pressure higher than the pressure to which said relatively high boiling point hydrocarbon oil was previously subjected.

4. A continuous process for cracking hydrocarbon oils, comprising simultaneously advancing in independent streams a relatively high boiling point hydrocarbon oil and a relatively low boiling point hydrocarbon oil through a heating zone, subjecting the stream of relatively low boiling point hydrocarbon oil to higher conditions of temperature and pressure than maintained on the stream of relatively high boiling point hydrocarbon oil, delivering the heated oil from said independent streams to an enlarged zone, maintaining a pressure in said enlarged zone in excess of the pressure maintained on said stream of relatively high boiling point hydrocarbon oil, and subjecting vapors evolved from the oil to dephlegmation and condensation.

5. A process of oil conversion, comprising maintaining a body of heated hydrocarbons in an enlarged zone, where substantial vaporization occurs, subjecting vapors to reflux condensation, to condense the heavier vapors, passing the reflux condensate resulting from the condensation of the heavier vapors in an advancing stream through a heating zone, where it is subjected to cracking conditions of temperature and pressure, delivering the heated condensate to said enlarged zone, simultaneously heating an independent stream of charging oil, for delivery to said enlarged zone, to a temperature sufficient to cause a substantial vaporization thereof in said enlarged zone, introducing said heated charging oil to the enlarged zone,

under a pressure in excess of the pressure maintained on said independent stream of charging oil during the heat treatment thereof.

6. An apparatus for cracking hydrocarbon oil, comprising a plurality of heating coils, an enlarged expansion chamber, means connecting each of said coils to said enlarged expansion chamber, means for supplying oil to each of said coils, means for maintaining independently controlled pressures on the oil in each of said coils, means, associated with the means connecting each coil to said expansion chamber, for introducing oil from the associated coil to the expansion chamber, at a pressure in excess of the pressure maintained on the oil in such associated coil.

7. A process for cracking hydrocarbon oil, comprising the simultaneous and independent subjection of a relatively low boiling point hydrocarbon oil and a relatively high boiling point hydrocarbon oil to higher and lower cracking conditions of temperature and pressure respectively, thereafter commingling the heated oils in a common zone maintained under a pressure higher than the pressure to which said relatively low boiling point hydrocarbon oil was previously subjected.

30 GUSTAV EGLOFF.
